ATTORNEY

UNITED STATES PATENT OFFICE.

JIM ALEX BOATWRIGHT, OF THOMSON, GEORGIA.

DISPLAY HANGER.

Application filed November 29, 1927. Serial No. 236,515.

This invention relates to hangers primarily adapted for displaying merchandise in shops, department stores and the like.

An object of the invention comprehends a hoop member upon which the merchandise may be suspended and viewed from all directions within the store.

Another object of the invention contemplates a swivel support adapted to permit rotation of the hoop when showing a customer the particular goods advertised upon the hoop instead of walking completely around the same.

A further object of the invention embodies alarm elements carried by the hanger which will notify the store keeper of the presence of shop lifters and other unauthorized persons when the merchandise is removed from the hanger.

With the above and other objects in view, the invention further consists of the following novel features and details of construction, to be hereinafter more fully described, illustrated in the accompanying drawings and pointed out in the appended claim.

In the drawings:—

Figure 1 is an elevation of the invention.

Figure 2 is a sectional view taken on line 2—2 of Figure 1.

Figure 3 is a sectional view taken on line 3—3 of Figure 1.

Figure 4 is a fragmentary perspective view of the lower portion of the invention, illustrating the arrangement of additional merchandise supports.

Referring to the drawings in detail, wherein like characters of reference denote corresponding parts, the reference character 10 indicates a hoop preferably formed of wire and of a sufficient gauge to support merchandise of different weights. The hoop is crimped, as indicated at 11, at appropriate points thereon to facilitate engagement with and to prevent displacement of loop portions 12 upon the adjacent ends of guys 13. A disk member 14, provided with openings 15, are adapted to receive the upper hooked end 16 of the guys 13. A pipe section or rod 17 extended centrally through the disk 14 is provided with a nut 18 upon the lowermost end thereof immediately beneath and engageable with the undersurface of said disk. A stop collar 19, carried by the pipe section or rod 17, is provided with a setscrew 20 adapted for biting engagement therewith and to repose upon the

upper side of the disk member 14 to prevent canting of the latter as well as the hoop 10.

A sleeve member 21 adapted to receive the uppermost end of the rod 17 is adapted for threaded engagement at the uppermost end thereof with said rod and held in a desired regulated and adjusted position through the instrumentality of a setscrew 22 adapted for biting engagement with said rod. A thimble 23 being threadedly engaged with the uppermost end of the rod member 17 is provided with a restricted entrance opening 24 in one end thereof which is adapted to receive a shaft member 25 therethrough. A head 26 carried upon the lowermost end of the shaft 25 within the thimble 23 is adapted for engagement with one wall of the thimble 23 around the restricted entrance opening 24 therein. The shaft 25 being provided with an eye 27 upon its opposite end adapted to receive the open end of a hook 28 therein.

A spring yoke 29 having connection at its ends upon the upper side of a disk member 14 is extended throughout the major portion of its length between the guys 13.

Bells or other signal devices 30, projected at inclinations from the spring yoke, will cause the hammers to strike the bells when merchandise is removed from any point upon the hoop, whereby shop lifters may be more readily detected and apprehended.

Another cardinal advantage of the invention resides in the fact that the displaying of a merchandise, in the manner as best illustrated in Figure 5 of the drawings, a customer could readily remove a particular merchandise and walk up to the counter and say "I want this" and pay the purchase price. The invention may thus be called a self-serving display device. The invention will also overcome a great difficulty as experienced in store-keeping to make it a practice to display hosiery and other goods within marked boxes. The customers generally pick up several pair at a time, and not being aware of the price, misplace the hosiery and as frequently occurs, higher price merchandise is placed within the less costly marked boxes and the merchandise is eventually sold at a loss.

Arms 31, such as illustrated in Figure 4 of the drawings, may be employed for use upon the hoop 10 in the event it is desirous to support additional merchandise.

The invention is susceptible of various changes in its form, proportions and minor

details of construction, and the right is herein reserved to make such changes as properly fall within the scope of the appended claim.

5 Having described the invention, what is claimed is:—

A display hanger comprising a hoop having a multiplicity of crimped portions thereon, a plurality of guys having the 10 lowermost ends thereof looped within the crimped portions of the hoop, a disk, the uppermost end of the guys terminating to provide hooked ends adapted for connection

with the disk, a rod upstanding from the disk, a sleeve member adjustably mounted thereon to raise and lower said hoop, a thimble carried upon the uppermost end of the rod, a shaft extended within the thimble and having an enlarged head thereon adapted to provide a swivel connection therebetween to permit rotation of said hoop, a spring yoke carried by the disk, and bells suspended from the yoke.

15 In testimony whereof I affix my signature.

20 JIM ALEX BOATWRIGHT.
